TICKET STACKING MACHINE

Richard L. N. Weingart, New York, N. Y.

Application November 4, 1947, Serial No. 784,037

6 Claims. (Cl. 232—1)

1

This invention relates to ticket receptacles designed primarily, although not exclusively, for use in motion picture theatres.

It is a common practice in theatres having a continuous program and where seats are not reserved, for the ticket collector to tear the patron's ticket in half, return one portion to the patron as his receipt, and deposit the remaining stub in a ticket receptacle. These stubs are thereafter sent to the theatre accounting office. Heretofore, no satisfactory means has been devised for preserving the order of the stubs as they are deposited in the receptacle. Thus, it has been impossible to detect a practice whereby stubs are not returned to the patrons, the whole ticket or tickets being surreptitiously returned to the ticket seller who sells them again without accounting for the purchase price.

Tickets are generally consecutively numbered, the number appearing at each end thereof, and if the stubs of all tickets sold are deposited in the ticket receptacle, and the relative order of deposit preserved, such stubs should be arranged substantially in numerical order since patrons ordinarily proceed directly from the ticket seller to the ticket taker. Thus, if accounting office notes any marked variation from a consecutive numerical arrangement of ticket stubs, there is a fair presumption that dishonest practices are prevalent.

An important object of the present invention is to provide a novel ticket receptacle having plural ticket spindles which can be successively positioned so as to receive the apertured ticket stubs thereon and thus preserve the sequence of receipt by the ticket collector. In most instances, the ticket will have pre-punched holes, but the spindle may have a sharp point for punching the hole. The ticket receptacle further permits the theatre accounting office to detect missing tickets as well as forged tickets bearing numbers which duplicate the numbers of genuine tickets.

Another object of the invention is to provide improved means for applying support to the spindles adjacent their upper ends while permitting free downward movement of the ticket stubs thereon. This improvement is of considerable importance, since if the machine is to have any considerable capacity, the spindles should be of considerable length—of the order of three feet. They must be of sufficiently small diameter to be received in the hole of usual size in the ticket, and accordingly support of the spindle at the

2

lower end only, regardless of how sturdy it may be, is nevertheless insufficient.

The improvement in this connection consists in providing a support for the upper section of the spindle, the support being formed with a substantially V-shaped recess. The spindle is appropriately mounted in a rigid fashion at its lower end so as to cause its upper end to be tensioned against the recess. This spring tension is generally directed towards the axis, but it may also be exerted in any other direction. The spindle has sufficient resiliency to permit it to be moved against the spring tension away from the support to permit ticket stubs applied at the upper end of the spindle to pass below the support. The edges of the V tend to guide the spindle back into the root of the recess when it is released.

A still further object of the invention is to provide a ticket receptacle with plural spindles wherein only one spindle is accessible at one time. The several spindles are mounted on a rotatable spindle assembly which successively advances one spindle to an opening in the housing.

The several spindles are consecutively numbered, and each time the ticket stubs are removed, regardless of whether or not all of the spindles are filled, spindle number one is turned to starting position. Accordingly, another object of the invention is to provide improved means for locking the spindle support against further rotation after the last spindle has been filled with tickets.

Yet a further object of the invention is to provide improved means for removing the ticket stubs from each spindle while preserving their sequence of receipt by the ticket collector.

In the drawings:

Fig. 1 is a perspective view of a ticket receptacle embodying the present invention, parts of the housing being broken away to show the internal construction.

Fig. 2 is a broken perspective view of the machine with the housing in opened position.

Fig. 3 is a top view of the mechanism with parts broken away.

Fig. 4 is a side view with the casing and parts of the mechanism broken away.

Fig. 5 is a plan view of the detent mechanism.

Fig. 6 is a broken perspective view of one of the ticket spindles.

Fig. 7 is similar to Fig. 6, but shows the means of removing the tickets from the spindle.

The apparatus of the present invention is arranged to be mounted within a housing including a base wall 10, fixed side walls 11, a side wall or door 12 hinged at 13, and an upper wall or

cover 14 hinged at 15, the two latter walls being arranged to be opened for the purpose of removing stubs from the spindles 16. A plurality of these spindles are rigidly mounted at their lower ends in bushings 20 secured to a disc 21. A hub 22 is secured centrally of the disc, and the disc and hub rotate on a vertical shaft 23 journaled in a bearing 24 secured centrally of base 10. A second disc 25 is secured by means of a hub 26 adjacent the upper end of shaft 23, and the spindles project above such disc as shown at 41. This disc is generally circular, but is provided with substantially V-shaped cut-out portions 27 in equally-spaced relation about its periphery, except as hereinafter noted, and at the center of each V-shaped portions there may be formed a semi-circular recess or notch 30.

The vertical bore (not shown) in each bushing or socket 20 is substantially parallel with the axis of shaft 23. Recesses 30, however, which receive the upper ends of spindle 16 are shown as being disposed in a circle of greater diameter than the circle within which sockets 20 are disposed. Thus, spindle 16 which is preferably made from resilient steel is spring-pressed into recesses 30, or if such recesses are omitted, then into the root of the V. In other words, if disc 25 were removed, spindle 16 would assume a position generally parallel with the axis of shaft 23 instead of the inclined position shown in the drawing. It is thus clear that each spindle is at all times under a bending stress, the stress being increased when the upper end is moved away from its supporting notch to allow a ticket to pass below disc 25. Notches 30 may alternatively be disposed in a circle of the same or of smaller diameter as bushings 20, and the bore in the bushing appropriately changed to bias the spindle inwardly. Adjacent each recess 30 is a number, the several recesses being consecutively numbered, as shown in Fig. 3.

The shaft passes through a hole 29 in cover 14, and at its upper end the shaft is provided with a knurled knob 31, and below the knob there is an indexing disc 32 having numbers corresponding to the numbers on disc 25. By providing bearing 24 of approved rigidity, there is no particular need for providing a second bearing adjacent the upper end of shaft 23. Such bearing may, however, be employed if desired.

Upper hinged cover 14 is provided with downwardly-extending side walls 33, and at the front of the machine there is a cut-out portion defined by opposed, diagonally-inclined walls 34 connected by a third diagonally-inclined wall 35. A horizontal wall 36 is secured to the lower edge of these opposed, inclined walls 34. This horizontal wall 36 is further provided with a cut-out portion 37, and at the outer terminals of such cut-out portion, and aligned therewith, are cut-out portions 38 in walls 34. Cut-out portions 38 are provided to permit such upper terminals 41 of the spindles to pass through such walls.

In the arrangement shown, there are six consecutively-numbered spindles which are substantially equally spaced, except that the spacing between the No. 6 and No. 1 spindles is double that of the others. In this area, on the upper surface of disc 25 there is imprinted a notation to the effect that the spindles are "Full."

The following means are provided for permitting step-by-step rotation of the spindles in one direction only, and for centering each spindle successively in ticket-applying location. A detent lever 42, journaled at 43 on a bracket 44, which is secured to one of the side walls 11,

Lever 42, which is urged in one direction by a spring 47, is provided along one edge thereof with a substantially straight section 39 which is generally tangent to a circle of which pivot 43 is the center. Adjoining the inner terminal of the straight edge there is formed a semicircular notch 45 which merges into a straight section 46 which bears an angular relationship to edge section 39.

As the spindle-carrying assembly is rotated, the bushings 20 successively are engaged by the notch 45 of lever 42, and the rotating spindle assembly thus centers one spindle in ticket-applying position while the others are concealed within the housing. It will thus be apparent that the spindle-carrying assembly may be rotated in a counter-clockwise direction, when viewed from above, and at each step of the rotation the lever engages a successive bushing 20. Reverse rotation is prevented by the trailing edge of notch 45 contacting such bushing. It was earlier pointed out that the bushings 20 are equally spaced around the periphery of disc 21, and since there is double the space between spindles Nos. 6 and 1, a solid bushing 50 having no spindle supporting function may be disposed on the lower disc between such spindles.

After spindle No. 6 has been filled, the spindle assembly may be rotated one further increment, at which point lever 42 engages solid bushing 50. Further rotation is prevented by means of hook 51 carried by disc 21 which engages post 52 carried by door 12.

Upper hinged wall 14 is arranged to be held in closed position by means of an apertured bolt 53 which receives a lug 54 carried by door 12 when the latter is closed. A lock 55 retains the latter in closed position. Door 12 may further be provided with slots 60 for receiving special tickets which fall into a receptacle 61 on the inner surface of door 12.

The upper end 41 of each spindle 16 is provided with a tapered vertical slot 62. After the tickets shown at 63 have filled the spindle, they may be removed while preserved in their order of deposit by means of a string 64 which is inserted in slot 62. The tickets are then moved upwardly off the spindle, as shown in Fig. 7, the ends of the string then tied and the tickets sent to the accounting office. If desired, a tamper-proof lead seal may secure the ends together.

A closure flap 66, hinged at 67, may also be provided for closing opening 37 in plate 36. This closure flap may be disposed in open or vertical position, as shown in Fig. 4, and in closed or horizontal position, as shown in Fig. 3. It is provided with a recess 68 which receives the exposed spindle and locks it against rotation. Any suitable means (not shown) operable from the outside of the housing may be employed for manipulating the flap to closed position and for locking it in such position. When this is done, the entire machine is locked and tickets can neither be deposited on the spindles nor removed therefrom.

The operation of the machine is as follows. After all tickets have been removed from the spindles, the doors are closed and the spindle assembly rotated to position the number one spindle within the opening in the cover. The ticket collector then receives tickets from the patrons, tears them in half, and places the stubs on the upper end portion of the exposed spindle. The tickets in this position are prevented from passing downwardly on the spindle because of the

support afforded by upper disc 25. The spindle is then moved forwardly to the position shown in broken lines at 16' in Fig. 4, thus permitting the tickets to be pushed or to fall downwardly on the spindle. The forward movement of the spindle (away from the axis) is more convenient than a rearward or sidewise movement, but the spindle assembly may be appropriately modified to vary the position of the recess and hence the direction of movement of the spindle to allow the ticket to clear the upper support.

As soon as the number one spindle has been filled with tickets, the spindle assembly is rotated to position the number two spindle within the opening. Thus, the tickets are always applied to the spindles at the same point. This operation is repeated until all spindles have been filled. When the spindle assembly is moved one increment of rotation beyond the Number 6 spindle, the entire assembly is locked against forward or rearward rotation, the former being prevented by contact of hook 51 with fixed post 52 and the latter being prevented by the trailing edge of notch 45 in lever 42 contacting bushing 50. The covers may then be opened and a cord 64 inserted within slot 62 at the end of one of the spindles. Since the slot is tapered, it acts as a clip to hold one end of the string. The spindle may then be moved outwardly to the position shown at 16" in Fig. 2 and the tickets moved upwardly onto the cord, after which the ends of the cord are tied. This operation is repeated until all of the spindles have been cleared of tickets.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What I claim is:

1. A ticket receptacle including plural ticket spindles for receiving apertured tickets, a rotatable member for the spindles including a lower support upon which the lower ends of the spindles are rigidly mounted with their upper ends spring biased towards the axis of rotation, an upper support having spaced notches receiving the upper terminal sections of the spindles, such upper terminal sections being movable outwardly from the notches against the spring bias to permit tickets received on the spindles to pass below the upper support, a housing for the spindle assembly including an upper wall having an opening permitting the upper end of one spindle only to be exposed for ticket application, means for preventing rotation of the rotatable member as each successive spindle is moved to ticket-applying position, and a closure flap for the opening in the upper wall and having a recess which receives the spindle in the opening and prevents rotation thereof.

2. A ticket receptacle including a spindle for receiving apertured ticket stubs, means for rigidly mounting the lower end of the spindle, and a plate having a recess for receiving and affording support for the upper section of the spindle, the spindle being spring biased against such recess but being movable outwardly therefrom against such spring bias to permit a ticket ap-

plied to the upper end of the spindle to pass below the plate, the spindle having a spring slot at its upper end for receiving a cord for stringing the ticket stubs when they are removed from the spindle.

3. A ticket receptacle including plural ticket spindles for receiving apertured tickets, a movable assembly for supporting the spindles including an upper plate having spaced notches around its edges which receive the upper sections of the spindles, a lower plate upon which the lower terminals of the spindles are rigidly mounted, means for urging the spindles in the direction of the notches to cause their upper sections to be under a bending stress against such notches, such upper sections being movable outwardly from the notches under greater bending stress to permit the tickets applied to the upper ends of the spindles to pass below the upper plate and a housing for the assembly including an upper wall having an opening for the upper sections of the spindles and being of sufficient width to permit only one spindle to occupy the opening at one time.
- 25 4. A ticket receptacle including plural ticket spindles for receiving apertured ticket stubs, a spindle-carrying assembly including a vertical shaft journaled for rotative movement, a lower disc carried thereby upon which the lower ends of the spindles are rigidly mounted in spaced relation, an upper disc carried by the shaft and having spaced recesses about its periphery to receive the spindles adjacent their upper ends to afford support thereto, such spindles being biased inwardly under a bending stress to resiliently engage such recesses but being outwardly movable from the recesses under greater bending stress to permit tickets to pass below the upper disc, a housing for the assembly provided with an upper wall having a recess at the front defined by downwardly inclined side wall sections and a lower wall section having an opening to receive the upper section of the spindle and side wall openings through which the spindle may pass during rotation of the assembly, the distance between the spindles being greater than the distance between said side wall sections so as to expose only one spindle at a time for ticket application, detent means for positioning the spindle centrally of the side wall sections, and a stop for limiting further rotation of the assembly when the ticket spindles are filled.
- 55 5. A ticket receptacle including plural ticket spindles for receiving apertured tickets, a rotatable assembly for supporting the spindles including an upper disc having spaced notches around its periphery which receive the upper sections of the spindles, a lower disc upon which the lower terminals of the spindles are rigidly mounted on such axes as to cause their upper sections to be under a bending stress against the notches, such upper sections being movable outwardly from the notches under greater bending stress to permit the tickets applied to the upper ends of the spindles to pass below the upper disc, and a housing for the assembly including an upper wall having a downwardly extending recessed portion including a lower wall section having an opening for the upper sections of the spindles, opposed walls defining such recessed portion which are spaced apart a distance only sufficient to receive one spindle therebetween, such walls having openings communicating with the lower wall section opening to permit the spindles to be rotated through the recessed portion, and de-

tent means for securing a spindle substantially centrally of the latter opening.

6. A ticket receptacle including plural ticket spindles for receiving apertured ticket stubs, a spindle-carrying assembly including a vertical shaft journalled for rotative movement, a lower disc carried thereby upon which the lower ends of the spindles are rigidly mounted in spaced relation, an upper disc carried by the shaft and having spaced recesses about its periphery to receive the spindles being biased inwardly under a bending stress to resiliently engage such recesses but being outwardly movable from the recesses under greater bending stress to permit tickets to pass below the upper disc, a housing 15 for the assembly provided with a removable upper wall having a recess at the front defined by downwardly inclined side wall sections and a lower wall section having an opening to receive

the upper section of the spindle and side wall openings through which the spindle may pass during rotation of the assembly, said side wall sections spaced apart a distance less than the distance between the spindles so as to receive only one spindle at a time therebetween.
